ATTORNEY.

UNITED STATES PATENT OFFICE

JOHN P. FRANCE, OF COLUMBUS, OHIO

ATTACHMENT FOR MUSICAL INSTRUMENTS

Application filed May 2, 1927. Serial No. 188,935.

This invention relates to attachments for musical instruments and more particularly to devices for changing the pitch of brass instruments.

- 5 The object of the invention is to provide a device which may be slipped into the bell of an ordinary brass instrument, such as a cornet, to change the pitch of the instrument for example from B flat to C.
- 10 Another object of the invention is to provide such an attachment which will change the pitch of the instrument without requiring any change in the position of the tuning-slides of the valves of the instrument.

15 Other and more particular objects of the invention will hereinafter appear.

The drawing illustrates the device, in section, as fitted in the bell of a cornet or similar instrument.

- 20 The ordinary pitch-changing devices, usually consisting of adjustable or interchangeable slides which change the length of the pipe, require that every valve of the instrument be tuned as well as that the fundamental 25 of the instrument be changed.

In my device, in contrast, I make use of the well-known phenomenon that an appreciable decrease in the diameter of a pipe causes a change in pitch, to avoid the above difficulty. This effect is now made use of particularly in piccolos, where the bore is constricted toward the outer end in order that it may be made sufficiently long to provide room for the keys and at the same time be of the proper 35 pitch. By the use of a corresponding constriction at the bell of a brass instrument, I find that the pitch of the instrument can be raised, for example, from B flat to C, and that the constriction also produces a proportion- 40 ate effect on the sections of the tube cut in by the valves, so that it is unnecessary to tune these separately.

The drawing illustrates the preferred form of my device, in which "1" is a tapered 45 portion adapted to fit snugly within the bore of the instrument at the bell, "2" is a tapered recess leading to the restricted bore "3", which in turn is increased in size toward the end "4", where it emerges into the bell "5".

- 50 The exact sizes and proportions of the de-

vice are not material, as they must be changed to suit the bore and length of various instruments. Change in the size of the bore "3"—"4" affects the pitch more than any other one factor, and the device can be readily adjusted to a particular instrument by enlarging this bore to the proper size for that instrument.

The bell "5" opens directly from the bore at "4" and functions in relation to this bore 60 in exactly the same manner as the usual bell of the instrument does in relation to the usual bore. This bell may be made in any usual form so long as it does not become unsightly or cumbersome.

The taper "2" performs two functions,—it serves to concentrate the sound into the bore at "3" and at the same time it prevents the formation of a node at the rear of the device.

Having thus described my invention, what I claim is:—

1. Means for raising the pitch of a wind musical instrument having an outwardly flared bell, consisting of a member shaped to fit within the bore of said instrument at 75 the bell, said member having a narrow, tapered bore and the inner end of said member having a recess tapered toward said bore.

2. Means for raising the pitch of a wind musical instrument having an outwardly flared bell, consisting of a member shaped to fit within the bore of said instrument at the bell, said member having a relatively small bore increasing in size toward the outer end and the inner end of said member having a 85 recess tapered toward said bore.

3. Means for raising the pitch of a wind musical instrument having an outwardly flared bell, consisting of a member shaped to fit within the bore of said instrument at the 90 bell, said member having a narrow, tapered bore, a bell on the outer end thereof, and the inner end of said member having a recess tapered toward said bore.

4. Means for raising the pitch of a wind 95 musical instrument having an outwardly flared bell, consisting of a member shaped to fit within the bore of said instrument at the bell, said member having a relatively small bore increasing in size toward the outer end, 100

a bell on the outer end thereof, and the inner end of said member having a recess tapered toward said bore.

In testimony whereof I have affixed my
5 signature.

JOHN P. FRANCE.
